DESIGN FOR A SLIPOVER GARMENT FOR OUTER WEAR

Gwenyth Waugh, New York, N. Y.

Application September 18, 1945, Serial No. 122,160

Term of patent 7 years

(Cl. D3—26)

To all whom it may concern:

Be it known that I, Gwenyth Waugh, a citizen of the United States of America, residing in New York city, county of New York, and State of New York, have invented a new, original, and ornamental Design for a Slipover Garment for Outer Wear, of which the following is a specification, reference being had to the accompanying drawing, forming part thereof, wherein,

I claim:

The ornamental design for a slipover garment for outer wear, substantially as shown,

GWENYTH WAUGH.
